(57) **CLAIM**

We claim the ornamental design for a control panel, as shown and described.

DESCRIPTION

FIG. 1 is a perspective view of a first embodiment of a control panel of our design;

FIG. 2 is a front elevation view of the control panel of FIG. 1; FIG. 3 is a perspective view of a second embodiment of a control panel of our design;

FIG. 4 is a front elevation view of the control panel of FIG. 3; FIG. 5 is a perspective view of a third embodiment of a control panel of our design; and,

FIG. 6 is a front elevation view of the control panel of FIG. 5. The broken lines shown in the drawings illustrate portions of the control panel that forms no part of claimed design.
